(57) **CLAIM**

The ornamental design for a shoe outsole, as shown and described.

DESCRIPTION

FIG. 1 is a front perspective view of a shoe outsole showing our new design;

FIG. 2 is a bottom view thereof;

FIG. 3 is a rear perspective view thereof;

FIG. 4 is an opposite side front perspective view thereof; and,

FIG. 5 is an opposite side rear perspective view thereof. The broken lines immediately adjacent to the shaded area define the bounds of the claimed design and form no part thereof. The broken lines showing the remainder of the shoe represent unclaimed subject matter and form no part of the claimed design.
